UNITED STATES PATENT OFFICE.

RANKIN KENNEDY, OF GLASGOW, SCOTLAND, ASSIGNOR OF ONE-HALF TO
ROBERT DICK, OF SAME PLACE.

ELECTRICAL TRANSFORMER.

SPECIFICATION forming part of Letters Patent No. 447,569, dated March 3, 1891.

Application filed December 29, 1886. Serial No. 222,929. (No model.)

To all whom it may concern:

Be it known that I, RANKIN KENNEDY, a subject of the Queen of Great Britain and Ireland, and a resident of Glasgow, county of 5 Lanark, Scotland, have invented certain Improvements in the Transformation and Distribution of Electric Energy, of which the following is a specification.

My invention has for its object and comprises appliances for the distribution of electric energy in alternating currents from a center with safety, economy, and cheapness. The distributing-wires employed for the purpose of this invention are comparatively small 15 and light, a large amount of energy being transmitted in the form of a small current at a high pressure or electro-motive force. Thus a horse-power can be transmitted through a wire only one-tenth of an inch in diameter 20 with a loss of only one-tenth of a horse-power per thousand yards of wire if I maintain a pressure or electro-motive force at the distant ends of one hundred and fifty volts and maintain a current of five ampères. If I 25 multiply the pressure by ten and raise it to fifteen hundred at the distant ends and still maintain a current of five ampères, this wire a tenth of an inch in diameter will transmit ten horse-power with a loss of or rather at the 30 expenditure of only one-tenth of a horse-power per one thousand yards or at a loss of only one per cent. It being thus possible to transmit electric energy at such a small loss per one thousand yards provided I employ 35 high electro-motive force and small current it becomes of importance to apply cables or apparatus, whereby I may utilize small currents at a high pressure for electric lighting, transmission of power, and other purposes, 40 which is what my invention is desired to accomplish. In the present state of electrical engineering small currents at high pressure cannot be conveniently applied to useful purposes generally. It is therefore necessary to 45 transform the small currents of high pressure into the large currents of low pressure, which are demanded and required for electric lighting and other purposes.

Electric energy is equal to the current multiplied by the electro-motive force or press-

ure, and the product divided by seven hundred and forty-six watts is equal to the horse-power of the energy. Thus, if I have fifteen hundred volts pressure and five ampères current the energy would be equal to (fifteen 55 hundred multiplied by five equals seven thousand five hundred, divided by seven hundred and forty-six, equals) about ten horse-power. Now, if this were transformed into a safe and usual pressure—say one hundred volts and a 60 current of seventy-five ampères—I would still have the same amount of energy in a useful and applicable form, or (one hundred multiplied by seventy-five equals seven thousand five hundred, divided by seven hundred and 65 forty-six, equals) about ten horse-power, as before, and the said current at this pressure could be utilized to light up and maintain one hundred sixteen-candle incandescent lamps, and all transmitted through a wire one-tenth 70 of an inch thick one thousand yards long, and at a loss in the wire of only one-tenth of a horse-power.

I have found as general laws governing the distribution of electric energy, first, where the 75 consumption-circuits require constant electro-motive force the transformers should be connected in parallel or multiple arc order and supplied from main conductors at constant electro-motive force; second, when the consumption-circuit requires a constant current I have found that the transformers should be connected in series order to the mains and a constant current maintained in these mains; 80 third, it is necessary for the purposes of 85 economy and the supply of constant electro-motive force to the consumption-circuits that the transforming device, whether in the form of a machine, cable, or induction-coil, should, when the secondary or consumption-circuit 90 is open, or, in other words, when no consumption is going on, generate a counter electro-motive force nearly equal and opposite to the working electro-motive force in the main conductors, and also that this counter or opposing electro-motive force should decrease regularly and steadily as the consumption increases; fourth, where a constant current is to be maintained in the mains and a constant current supplied to the consumption-circuit 95 100

there should be no counter electro-mot 5 force in the transformer when no consumption is going on, but a counter electro-motive force must be generated in the transformer opposing the working electro-motive force immediately consumption begins, and this opposing electro-motive force should increase as long as the consumption of electric energy increases. These are the first clear state- 10 ments made of the four natural laws governing the distribution of electric energy by trans- formers, and having discovered these laws of the counter electro-motive force I have devised transformers which fulfill the require- 15 ments of these laws.

According to my present improvements for connection in parallel order with the mains and constant potential supply, my alternating-current transformer consists of a cable or 20 rope of insulated copper wires or strips of copper sheathed with soft iron. There may be any number of wires or strips in the cable and some may be insulated from the others, while others may be uninsulated in cases 25 where they have to be joined parallel. Good results are obtained where only seven wires are used, a central insulated wire forming a secondary circuit and surrounded by six bare wires forming a primary circuit, the whole 30 constituting a cable, which is then insulated by a layer of cotton, silk, or jute tape cov- ering all over. Over this is then wound a sheathing of soft iron, either of coiled wire, plates, or ring disks, preferably to a depth of 35 from an eighth to a fourth of the diameter of the seven-wire cable. The cable when used as a transformer may be coiled or put up into any shape or form most convenient for its being packed away.

40 In the accompanying drawings, Figures 1 and 2 are transverse and longitudinal vertical sections, respectively, of a cylindrical form of alternating-current cable or transformer constructed in accordance with my said improve- 45 ments, in which one large insulated copper round wire a' is used as the secondary-circuit conductor and six smaller insulated wires a' , connected up in series order, are used as the primary-circuit conductor, both 50 conductors constituting a cable or transformer which is covered over with a layer of cotton, silk, jute tape, or other insulating material c , and having an insulating material be- 55 tween the wires, (indicated at c'), and over 60 the whole is then applied a sheathing of coiled soft-iron insulated wire b outside, as shown at one end of Fig. 2; or it might be annular thin disks of soft sheet-iron, as shown at $b b'$ in Fig. 2 and in end view in Fig. 3, these 65 rings or plates being also insulated from each other by a coating of varnish or by thin strips of paper and made to inclose the whole cable or coil from end to end. Instead of using round iron wire for the primary and second- 70 ary circuit conducting-wires, flat or polygonal wires may be used.

Fig. 4 is a transverse section, and Figs. 5

and 6 are longitudinal sections at right angles to each other, respectively, of a modified construction of alternating-current cable or trans- 70 formers from the cylindrical form shown in Figs. 1, 2, and 3, and which is rectangular in transverse section, as shown in Fig. 4, constructed in accordance with the improvements of my invention. In this construction the 75 primary-circuit conductors a and the second- 80 ary-circuit conductors a' consist of six nar- row and four broad strips or bands, respect- 85 ively, of copper insulated from each other by a layer of cotton or other insulating ma- 90 terial c' , which may either be wound round the bands or compressed between them and all inclosed within an insulating-covering c , (indicated in gray and black lines, respect- 95 ively,) while the bands of copper are shown in section in Fig. 4. In this arrangement the primary-circuit conductors a are connected up in series order and the secondary-circuit conductors a' in parallel order. This cable or cable-transformer is inclosed within 90 a magnetic sheathing, casing, or shell of coiled wire or narrow bands b or ring-plates b' , re- 95 spectively, as described in reference to Figs. 1 to 3, an end view of one of these metallic ring-plates being shown in Fig. 7. These ring- 95 plates b' (shown in Figs. 3 and 7) might be punched out of soft sheet-iron as washers are usually punched.

Fig. 8, Sheet 2, illustrates a perspective view showing how my new or improved cable-trans- 100 former can be used in a system of distribution of electric energy for supplying any desired electro-motive force up to the maximum to the electric lamps or other translating devices placed in the consumption-circuit. In this 105 arrangement the secondary wire in the trans- 110 former is connected at A to the main con- ducting-wire A' , which is connected to the translating devices g at G, and at the different points B C D E connection is made by the 110 wires H between the secondary wire of the 115 transformer and a switch-board F , having separate studs numbered 1 2 3 4 for each of these respective wires or contacts.

The main conducting-wire B' is connected 115 to the movable switch or contact-maker F' , so that any desired electro-motive force is con- 120veyed to the lamps or other translating de- 125 vices g , placed at G, according to the stud with which the movable switch is placed in contact.

In the diagram, Fig. 9, I have illustrated how the cable in practice is made up into a coil and how the primary and secondary wires are connected in series. In this figure the 125 primary wires (indicated by thin lines) are distinguished by numerical figures 1 to 6 and the connections by light dotted lines. The first wire 1, which forms the one terminal end at x for current connection, has its other end 130 1' connected to the next wire 2, and the wire 2 has its other end 2' connected to the next wire 3, and the wire 3 has its other end 3' connected to the next wire 4, and the wire 4

- has its other end 4' connected to the next wire 5, and the wire 5 has its other end 5' connected to the next wire 6, and so on, if there are more primary wires in the cable. In this case the other end 6' of the wire 6 forms the other terminal end x' of the primary wires thus joined in series for current connection, the ends x and x' of the wires 1 and 6 being connected to the conductors leading from the alternating-current generator. The secondary wires $a b c$, which are indicated by thick lines and the connections by thick dotted lines, are also in this case connected in series. The first wire a is connected at the end a' to the next wire b , and the wire b has its other end b' connected to the next wire c , and so on, if there are more secondary wires. In this case the free ends y and y' of the wires a and c are connected to the main conductors of the consumption-circuit, as A' and B' in Fig. 8, through which currents would be transmitted when currents pass through the primary wires. The primary and secondary wires would be covered and embedded in insulating material, such as gutta-percha, and have a magnetic-iron outside sheathing of a few layers of coiled wire b^x , and, as indicated by b in Figs. 1 to 6, over the whole length, so as to form an iron-sheathed cable-transformer.
- The novel feature in these improvements is the application of an iron-sheathed cable of insulated conducting-wires, wherein one or more wires are used as a primary and one or more as a secondary circuit for the transformation of electric energy of alternating currents.
- Iron sheathing has heretofore been applied to coils of wire for the same purpose; but in that case, the coils of wire being of many turns, some of them are unavoidably far from the iron sheathing, and thus its effects are not uniform throughout the length of wire forming the coils.
- By my improvements I inclose the wires themselves from end to end in an iron sheathing, and this insures uniformity, besides great intensity of action, from end to end, and I do not require to wind this cable into any particular coil or form whatever. This proved cable is also conveniently made in long lengths of any suitable cross-section sufficient to carry the strength of current. For instance, if I have a current of six ampères in the primary-circuit wire a , that would in practice require to have a sectional area of at least two square millimeters. In the secondary circuit, where the large currents

circulate, the combined area of the wires a' forming this circuit would be equal to one square millimeter for every three ampères of 60 current.

In my improved cable the electro-motive force is directly proportional to its length—that is to say, the force increases from zero at one end to a maximum at the other—so 65 that any desired electro-motive force less than this maximum may be obtained by making a connection at proportionally lesser lengths of the cable, as shown in Fig. 8, Sheet 2. Thus with a cable of a length giving a 70 hundred volts pressure an electro-motive force of fifty volts could be obtained by making a connection at half-length and still maintain the continuity of the cable and the maximum pressure of the whole length; or the 75 cables may be made in coils of suitable lengths as transformers for any desired electro-motive force to be transmitted through them.

It is to be understood that this cable or cable-coil transformer, although described as a 80 secondary generator, may also be used as a main transformer of alternating currents of electric energy when placed between the dynamo-electric machines and the main conductors for transforming currents of low potential into currents of high potential in the 85 main lines by having the primary conductor as a short wire and the secondary conductor as a long wire.

What I claim is—

1. A cable for transformers of electric energy having insulated copper conductors for the primary and secondary circuits inclosed throughout their length within an outer sheathing of iron wires or plates, substantially as and for the purpose set forth. 95

2. A transformer of electric energy in the form of a cable and comprising the combination of an outer sheathing of iron wires or plates with inner primary and secondary 100 wires having connections made at any number of points along the length of the cable for the purpose of obtaining any desired electro-motive force less than the maximum, substantially as herein set forth. 105

In testimony whereof I have signed my name to this specification in the presence of two subscribing witnesses.

RANKIN KENNEDY.
